(57) **CLAIM**

We claim the ornamental design for a microperforation dental device, as shown and described.

DESCRIPTION

FIG. 1 is a perspective view of the microperforation dental device showing our new design;

FIG. 2 is a right view thereof;

FIG. 3 is a left view thereof;

FIG. 4 is an enlarged front view thereof;

FIG. 5 is an enlarged back view thereof;

FIG. 6 is a top view thereof; and

FIG. 7 is a bottom view thereof; and,

FIG. 8 is another perspective view thereof.

Portions of the microperforation dental device shown in broken lines form no part of the claimed design.

1 Claim, 6 Drawing Sheets
